(57) **CLAIM**

The ornamental design for a toy house, as shown and described.

DESCRIPTION

FIG. 1 is a front, perspective view of a toy house showing my new design;

FIG. 2 is a rear view thereof;

FIG. 3 is a front view thereof;

FIG. 4 is a rear view thereof;

FIG. 5 is a top plan view thereof;

FIG. 6 is a left side view thereof; and,

FIG. 7 is a right side view thereof.

The features shown in broken lines with consistent dash lengths illustrate portions of the toy house ornamentation and/or features that form no part of the claimed design.
